(57) **CLAIM**

The ornamental design for a folding knife, as shown and described.

DESCRIPTION

FIG. 1 is a perspective view of a folding knife, showing my new design;

FIG. 2 is a right-side elevation view thereof;

FIG. 3 is a left-side elevation view thereof;

FIG. 4 is a top plan view thereof;

FIG. 5 is a bottom plan view thereof;

FIG. 6 is front elevation view thereof;

FIG. 7 is a rear elevation view thereof; and

FIG. 8 is a perspective view thereof, wherein the unclaimed replaceable blade element is positioned separate from the knife.

FIG. 9 is a perspective view of the folding knife, wherein the blade holder is in its closed position;

FIG. 10 is another perspective view thereof, wherein the blade holder is in its half-opened position; and

FIG. 11 is a perspective view of the folding knife, similar to FIG. 8, but with the blade holder tab in a raised position; and,

FIG. 12 is an isolated perspective view with the tab lifted and the blade and name plate in broken lines.

The broken line features, the blade and the name plate in FIGS. 1-12 form no part of the claimed design.
